UNITED STATES PATENT OFFICE.

CHARLES A. MOORE, OF ST. PAUL, MINNESOTA.

TEMPERATURE-CHANGING AND AIR-CIRCULATING APPLIANCE.

Application filed August 15, 1924. Serial No. 732,347.

My invention relates to an improved appliance for affecting the temperature of and circulating air in a storage or other room to refrigerate or heat the room or ventilate it under refrigeration or heating.

One object of the invention is to provide an appliance of this nature wherein coiled pipe is employed as a duct for air and also as a container for a medium to affect the temperature of air within the duct.

Another object is to supply an appliance of this kind, wherein a duct for directing air from one level to another is formed of a series of superimposed coiled pipe sections, the pipe of each section being fed and drained independently of the pipes of the other sections.

A further object is to provide a device, as above, the pipes of the individual sections being connected with a common source of supply and a common drain, the inlet side of each pipe being fitted with cut-off mechanism to permit of selective use of the different sections of the duct.

An additional object is to provide an appliance of the instant type, the structural arrangement thereof making for simplicity, durability, efficiency and low cost of manufacture.

With the foregoing and other objects in view, which will appear in the following description, the invention resides in the novel combination and arrangement of parts and in the details of construction hereinafter described and claimed.

In the drawings, Fig. 1 is a side elevation of an appliance embodying my invention; Fig. 2 is a central, longitudinal sectional view thereof, the same being taken as on the line 2-2 of Fig. 1; Fig. 3 is an enlarged sectional view taken horizontally of Fig. 1 as on the line 3-3 of said Fig. 1; Fig. 4 is a detail sectional view taken on the line 4-4 of Fig. 3 and Fig. 5 is an elevational view of one of the duct sections and showing the length of pipe, which constitutes the same, turned coil upon coil.

Referring to the drawings, an embodiment of the present invention will be seen in Fig. 1. This structure is placed in a storage or other room to circulate the air therein with or without ventilation and to refrigerate or heat the room as may be desired. Said structure includes an outer duct A and an inner duct B arranged concentrically

within said outer duct. The outer duct A has a cap C thereon. An upwardly extending branch-duct 10, reaching through and carried by the cap C slips, at its lower end, into the upper end of the inner duct B and terminates at a point short of the ceiling of a room in which the structure is placed. The lower end of the inner duct B depends beneath the lower edge of the outer duct A, said inner duct being supplied with two branch-ducts 11, 12, the former being projected through the wall of the room and into the outer air and the latter reaching under the wall of the outer duct A and into the room. These branch-ducts 11, 12, are respectively fitted with a damper 13 and a plug 14 through the medium of which the flow of air may be controlled. A branch duct 15 rising from the cap C and communicating with the outer duct A is lead into the outer air from the upper portion of the room in which the appliance is installed, said branch-duct 15 being provided with a thimble 16 fitted with a plug 17 and with a damper 18 above the thimble.

The inner duct B and its branch-ducts 10, 11 and 12 are simple sheet metal conduits. The outer duct A, however, is of a peculiar and novel construction, which will now be described. Said duct A consists of a series of superimposed, vertically aligned ring-like sections *a*. Each section comprises a length of pipe 19 turned, coil upon coil, as shown, said sections being assembled with the pipes 19 winding in the same direction. To unite said duct sections *a* in unitary form and to support the same, I provide a plurality of spaced standards 20, which, as illustrated, consist of channel irons, the flanges thereof being turned against the outer sides of the duct sections *a* and the lower ends of said channel irons being seated on a ring-like base 21 of angle iron. Inside of the duct sections *a* are straps 22, one for each standard 20, each strap opposing its respective standard. Bolts 23 reaching through said straps 22 and standards 20 pass between turns of the pipes 19 and are supplied with nuts 23^a tightened against the outer faces of the webs of the standards 20. Said bolts 23 may be of the ribbon type, and the pipes 19 may be indented at points of contact with said bolts, whatever the type thereof to receive the same and thereby form comparatively tight walls in the duct A. The ends of the pipe 19 of each

duct section α are turned outward (Fig. 3) and flanged as at 19° . Rising side by side on the outside of the duct A are two manifolds 24, 25, the former being adapted to be connected with a source of supply of temperature affecting medium and the latter with a drain or a pipe returning to said source of supply. Nipples 25 a connect the upper ends of pipes 19 with the manifold 25 and connections 24 a , fitted with valves 26, join the lower ends of said pipes 19 with the manifold 24. With the pipes 19 containing an effective refrigerating medium, the duct sections α become frosted sufficiently to close the limited spaces, if any, between the turns of pipe 19. This condition prevailing the walls of the duct are practically imperforate.

The cap C has a depending flange c thereon, which fits over the upper ends of the standards 20. At the lower end of the duct A is a skirt d of sheet metal, said skirt being fastened to the standards 20 by the lowermost bolts 23 therein. Being thus secured to the supporting standards 20, the skirt d , in turn, supports the inner duct B, through the medium of the branch ducts 11, 12 any suitable connection being made between said branch ducts and skirt as by means of fasteners 27.

30 From the foregoing, it will be understood that the parts of my appliance may be readily and economically constructed of stock materials and easily assembled.

My improvement is most frequently put to use in the conditioning of the air in storage rooms, whereby refrigeration is accompanied with internal circulation, mixed internal circulation and ventilation, or ventilation. In thus employing the appliance a refrigerating medium is directed through the manifolds 24, 25 into and out of the duct sections α , such sections, as desired, being selectively employed through the manipulation of the valves 26. Internal, refrigerated circulation of air in a room is accomplished by closing the damper 18, in the branch-duct 15, removing the plug 17 from the thimble 16 in said branch-duct, closing the damper 13 in the branch-duct 11 and removing the plug 14 in the branch-duct 12. Mixed refrigerated ventilation and internal circulation is accomplished in changing the adjustment, above noted, by opening the dampers 13, 18 partially or fully, said condition being converted to that of refrigerated ventilation by applying the plugs 14, 17. In thus employing the device as a refrigerating element the valve 26 of any section A may be adjusted to fully or partially open that particular section to the inlet manifold 24 or to entirely cut off the same therefrom. This feature provides for economically and effectively meeting different operating requirements. The ability to de-frost the sections α of the duct A without interrupting the oper-

ation of the appliance is one advantage of the present structure. Selectively controlled by the valves 26, these sections α may be shut off, at will, from the source of supply of refrigerating medium, thus allowing the frost 70 on the section or sections α , in disuse as conductors for said medium, to melt, whereby better results may be obtained from the medium in the refrigerating process. In this connection it will be noted that I contemplate 75 the provision in a duct of one section within another, each consisting of pipe turned coil upon coil, the pipe of each section having an individual cut-off valve fitted thereto and permitting of the selective regulated use or 80 the disuse of said sections.

Under heating, with a suitable heating medium flowing through the pipes 19 of the duct sections α , conditions of circulation and ventilation, as above explained, may be 85 had. The flow of air in such cases will be upward through the ducts A, B, instead of downward therethrough, as under refrigeration, use of the dampers 13, 18 and plugs 14, 17 being made according to the condition 90 desired. In this connection it will be understood that the valves 26 controlling the coil sections α may be operated under heating, the same as under refrigeration, whereby immediate and selective control of the individual coil sections α is brought about. 95

Changes in the specific form of my invention, as herein disclosed, may be made within the scope of what is claimed without departing from the spirit of my invention. 100

Having described my invention, what I claim as new and desire to protect by Letters Patent is:

1. In an appliance of the class described, a duct for directing air from one level to another consisting of a plurality of superimposed sections, each section comprising a length of pipe coiled turn upon turn, spaced standards supporting said duct sections, tying the turns thereof together and uniting 105 said sections in a unitary structure, an inlet manifold for a temperature affecting medium, said manifold being connected with one end of each coiled pipe and supported therethrough by said standards, and an outlet manifold connected with each of the other ends of said coiled pipes and also supported therethrough by said standards. 110

2. In an appliance of the class described, an outer duct structure formed of pipe coiled, turn upon turn, and spaced standards supporting said pipe and tying together the turns thereof and an inner duct passing through and carried by said outer duct structure. 115

3. An upright duct structure for directing air from various high levels in a room to various lower levels therein, said structure comprising superimposed sections, each consisting of a coiled pipe, means for introduc- 120

ing a refrigerating medium into the pipes of combinations thereof providing a tight said sections, selectively, the pipe of each walled duct, the upper and lower extrem-
section having spaces between the turns ities thereof varying in elevation. ¹⁰
thereof restricted to permit of the frosting In testimony whereof, I have signed my
over of the same in the presence of a refrig- name to this specification.

CHARLES A. MOORE.
